UNITED STATES PATENT OFFICE

2,495,121

VEGETABLE CUTTER

William H. Moore, Buffalo, N. Y.

Application March 21, 1946, Serial No. 656,093

2 Claims. (Cl. 146—78)

1

This invention relates generally to certain new and useful improvements in machines for cutting or slicing vegetables and the like, and more particularly to a machine for home or domestic use.

One of its objects is to provide a machine of this character which is simple and compact in construction, positive, reliable and efficient in operation, and which is easy to operate.

Another object of the invention is to provide a vegetable cutting machine which is so designed and constructed as to enable vegetables and fruits to be sliced in a uniform manner as well as to be diced or cubed for use in salads and the like.

Other features of the invention reside in the construction and arrangement of parts herein-after described and particularly pointed out in the appended claims.

In the accompanying drawings:

Figure 1 is a side elevation, partly in section, of the slicing machine embodying my invention. Figure 2 is a horizontal section thereof taken on line 2—2, Figure 1. Figure 3 is an enlarged, fragmentary longitudinal section taken in the plane of line 3—3, Figure 2.

Similar characters of reference indicate corresponding parts throughout the several views.

Referring now to the drawings, 10 indicates a portable frame or standard on which the working parts of the device are mounted, such standard terminating at its bottom in a base 11 on which a bowl 12 or like vessel is adapted to be placed for receiving the fruits or vegetables sliced by the machine. Applied to this standard are relatively movable telescoping head and cutter members 13 and 14 between which the vegetable is placed and adapted to be sliced when such members are brought into operative relation with each other and with the resulting slices being discharged into the bowl 12. The cutter member 14 is stationary relative to the vegetable-engaging head, and is detachably mounted in an opening 15 formed in a platform 16 overhanging the base 11. The blades 17 of the cutter member may be arranged as desired to cut the vegetable into slices or other shaped forms, and by preference and spaced below these blades to provide a horizontal slot or guideway 18 are guide vanes 19 which are in aligning or registering relation with the blades and between which the sliced particles pass or discharge into the vessel for receiving them. Guided for reciprocating movement on this platform at right angles to the movement of the head member 13 is a dicing cutter 20 which is adapted to be projected into and out of the cutter guideway 18 subsequent to each operative stroke of the

2

head member to sever the sliced particles into diced or other forms of varying lengths desired.

The head member 13, which is ribbed or slotted as shown, to mate and telescope into the cutter member 14 to eject the cut particles therefrom into the vessel 12, is applied to the lower end of a vertically movable plunger 21 guided in a suitable bearing 22 formed on the standard for continuous or intermittent movement. Formed on this plunger is a rack 23, with which a ratchet-actuated pinion 24 cooperates, a vertically-swinging lever 25 being employed for actuating the pinion and in turn the operative stroke of the plunger-head. If desired, a spring 26 may be applied to the upper end of the plunger with one end abutting against the bearing 22 and its other end against a collar 27 fixed on the plunger, whereby the latter is constantly urged upwardly to bring its head member clear of the platform 16. The plunger has a vertical slot 28 therein which is adapted to be engaged, under certain operating conditions, with a releasable bolt 29 for limiting the downward travel of the plunger.

The dicing cutter 20 is preferably actuated by 25 a solenoid 30 mounted on the platform 16 and having its movable core 31 connected to the inner end of such cutter. A spring 32 coiled about the projecting inner end of this core and abutting at one end against the solenoid and at its other end against a collar 33 applied to such core serves to normally urge this cutter to a retracted position. A switch 34 included in the circuit of the solenoid is provided for controlling the projection of the cutter at the will of the user to its dicing position. If desired, this dicing cutter may be 35 manually actuated by a vertically-swinging lever 35 pivoted adjacent the inner end of the platform and having a cam 36 connected thereto in wiping operative relation to the collar 33 of the solenoid-core 31, so that when such lever is swung forwardly the dicing cutter is projected into the guideway 18 of the cutter member 14 to transversely cut or dice the vegetable particles sliced by the latter.

Pivottally mounted on the standard 10 in governing relation to the releasable bolt 29 and the switch 34 is a manually actuated lever 37 having a pendant latch 38 which is normally engaged with the bolt to retain it in a released position, a spring 39 connected to said bolt normally urging it into operative engagement with the plunger 21. This latch is guided on a bracket 40 projecting outwardly from the bearing 22, and a spring 41 interposed between this bracket and a 50 collar 42 on the latch normally urges the latter

upwardly to a bolt-latching position and the lever 37 to its normal or switch-opening position. By this construction when it is desired to dice the vegetables, the governing lever 37 is depressed at the proper time alternately with the reciprocating slicing movements of the plunger, which closes the solenoid circuit to actuate the dicing cutter 20 and at the same time release the latch to cause the bolt to be projected into the plunger-slot 28 in readiness to limit the downward stroke of such plunger to a point where its head 13 will not intersect the plane of travel of the dicing cutter. Suitable stops 43 may be provided for limiting and cushioning the forward and return movements of the dicing.

While manifestly simple, compact and inexpensive in construction, this improved machine is very efficient for slicing or dicing fruits and vegetables, it is easy to operate and it is so designed that it is not liable to get out of order.

For slicing purposes, the vegetable or fruit is placed between the members 13, 14 and the head lowered by the handle 25 to force the vegetable downwardly thru the cutter 14 to slice it and cause the slices to drop by gravity into the bowl 12. For dicing, the vegetable is fed in intermittent fashion thru the cutter 14 and between each downward stroke of the plunger gaged by the pull on the lever 25, the dicing cutter 20 is actuated to cut the vegetable at right angles to the slicing cut. The operating stroke of the dicing cutter may be effected manually by the lever 35 or electrically by depressing the lever 32 to energize the solenoid 30.

I claim as my invention:

1. A device of the character described, comprising a frame, slicing and dicing cutters mounted on said frame at substantially right angles to each other, the slicing cutter being stationary and the dicing cutter being movable transversely of the former, a plunger guided on said frame including a vegetable-engaging head in opposing relation to the stationary cutter, a releasable bolt disposed in operative relation to the plunger and projecting to a position for limiting its operative stroke during the operation of the dicing cutter means operatively connected to said dicing cutter for reciprocating it into and

out of its dicing position, a latch for normally retaining said bolt in its released position, and an actuating device common to said bolt-retaining latch and said dicing cutter reciprocating means for governing the release of the bolt to its operative stop-limiting position and the initiation of the dicing cutter to its projected operative position.

2. A device of the character described, comprising a frame, slicing and dicing cutters mounted on said frame at substantially right angles to each other, the slicing cutter being stationary and the dicing cutter being movable transversely of the former, a plunger guided on said frame including a vegetable-engaging head in opposing relation to the stationary cutter, solenoid means including a control switch operatively connected to said dicing cutter for projecting into and out of its dicing position, a releasable bolt disposed in operative relation to the plunger and projectable to a position for limiting its operative stroke, a latch for normally retaining the bolt in its released position, and an actuating lever disposed in correlation with said control switch and said latch for governing the actuation of such parts to their switch-closing and latch-released stroke-limiting positions, respectively.

WILLIAM H. MOORE.
